UNITED STATES PATENT OFFICE.

ROBERT LEE, OF CINCINNATI, OHIO.

LOCK-STRIKE.

SPECIFICATION forming part of Letters Patent No. 269,799, dated December 26, 1882.

Application filed February 1, 1882. (Model.)

To all whom it may concern:

Be it known that I, ROBERT LEE, of Cincinnati, Hamilton county, Ohio, have invented a new and useful Improvement in Lock-Strikes, 5 of which the following is a specification.

My invention relates to an improvement in those lock-strokes in which a yielding and resilient lip or nosing receives the impact of the lock-bolt, and serves to hold the latter fast 10 until retracted by the knob in the ordinary action of opening the door.

In the accompanying drawings, Figure 1 is a horizontal section, showing the bolt in the act of striking. Fig. 2 is a similar section, 15 showing the same engaged behind the striker-lip. Fig. 3 is a perspective view of the striker, seen from the rear and with the lip retracted.

A may represent an ordinary snub-bolt of a latch-lock. B is my striker-plate, having 20 bolt-orifice b, recessed at b" into the return or face-flange b' at the outer edge to permit the latch to pass. C is a yielding lip thereof, wholly within the plate, having two arms, c c', hinged at d to eyes D on the rear of the striker- 25 plate. A helical spring, E, whose extremities bear upon the striker-plate and lip, respectively, gives the lip a tendency to close to its effective or normal position on the complete entrance of the latch-bolt, as shown in Fig. 2. 30 Shoulders c" on the yielding lip C, abutting

against the rear wall of the plate B, operate as a gage or stop to limit the outward movement of the lip C in reaching its closed or normal position. The facing-flange or return b', projecting rectangularly from the plate B, 35 and which is preferably made flush with the door-jamb on its room face, serves the several useful purposes of a guard surrounding the lip, of hiding the otherwise unsightly excavation in the jamb made necessary to permit 40 play of the yielding lip, of firmly bracing together the upper and lower portions of said plate, and also of affording an abutment, b'", for said lip, which receives any outward stress of the lock-bolt against it, thus wholly relieving 45 the lip-hinge from strain.

I claim—

The combination of striker-plate B, formed with return or face-flange b', opening b b", presenting abutment b'", on the side of the face-flange, and the yielding lip C, hinged within the striker-plate, having shoulders c" c', and adapted to recede inside of the abutment, as set forth.

In testimony of which invention I hereunto 55 set my hand.

ROBERT LEE.
